[57] CLAIM

The ornamental design for lamp switch adapter, as shown and described.

DESCRIPTION

FIG. 1 is a front perspective view of the lamp switch adapter, showing our new design;

FIG. 2 is a rear perspective view thereof;

FIG. 3 is a top plan view thereof;

FIG. 4 is a front plan view thereof;

FIG. 5 is a side elevational view taken from the left side of FIG. 6;

FIG. 6 is a rear plan view thereof;

FIG. 7 is a bottom plan view thereof;

FIG. 8 is a front perspective view of the lamp switch adapter, as being installed onto a lamp switch knob.

The broken line disclosure of the lamp in FIG. 8 is for illustrative purposes only and forms no part of the claimed design.
